UNITED STATES PATENT OFFICE

128,604

DESIGN FOR A BOTTLE OR SIMILAR ARTICLE

Arthur B. Shiplett, Zanesville, Ohio, assignor to Hazel-Atlas Glass Company, Wheeling, W. Va., a corporation of West Virginia

Application December 13, 1940, Serial No. 97,293

Term of patent 14 years

To all whom it may concern:

Be it known that I, Arthur B. Shiplett, a citizen of the United States, residing at Zanesville, in the county of Muskingum and State of Ohio, have invented a new, original, and ornamental Design for a Bottle or Similar Article, of which the following is a specification, reference being had to the accompanying drawing, forming part thereof.

Figure 1 is a plan view of the bottle showing my new design, with the conventional body being indicated by dot and dash lines; and

The characteristic features of my design reside in the neck portion of the bottle or similar article, shown in full lines.

I claim:

The ornamental design for a bottle or similar article, as shown and described.

ARTHUR B. SHIPLETT.
